ABSTRACT OF THE DISCLOSURE

An adjustable nozzle to diffuse gas passing through a plate has a tubular shank fixed in the plate with a castellated and threaded top over which there is screwed a pointed cap containing a pair of transverse apertures, the castellations serving as lateral gas exit orifices and as locking means to receive a locking pin passing through the transverse apertures in the cap.

BACKGROUND OF THE INVENTION

In fluidized bed dryers in which a heated gas passes upward through diffuser nozzles fixed in a partition plate to suspend fine particles for drying in the rising gas flow, the pressure drop and gas flow in individual nozzles can only be regulated, in conventional practice, by changing nozzles of one fixed orifice size to nozzles of another orifice size. Considerable variation in gas flow in different parts of a fluid bed dryer is required to overcome wall drag and other irregularities and provide uniform particle supporting upward flow.

SUMMARY OF THE INVENTION

Adjustable nozzles to diffuse gas passing through a fluid bed dryer partition plate each have a tubular shank adapted to be fixed in the plate, the tubular shank having a castellated and threaded upper end over which there is screwed a pointed cap containing a pair of transverse apertures, the castellations serving as lateral gas exit orifices and as locking means to receive a locking pin passing through the transverse apertures in the cap. Rotation of the cap on withdrawal of the locking pin, screws the cap upward or downward on the castellations to vary the size of the slits of the castellations appearing below the cap. This provides a plurality of adjustable orifices to vary the flow of gas therethrough. This nozzle is inexpensive to manufacture, it is easily adjustable, and it directs gas over a partition plate as required.

BRIEF DESCRIPTION OF THE DRAWING

FIGURE 1 is a vertical section through a fragment of a fluid bed dryer partition plate showing a side view of an adjustable diffuser nozzle fixed therein;

FIGURE 2 is a longitudinal, vertical section through the tubular shank of the diffuser nozzle;

FIGURE 3 is a top view of the tubular shank of the diffuser nozzle;

FIGURE 4 is a longitudinal, vertical section through the pointed cap of the diffuser nozzle;

FIGURE 5 is a bottom view of the cap; and

FIGURE 6 is a side view of a locking pin.

DESCRIPTION OF THE PREFERRED EMBODIMENT

Partition plate 10 of a fluid bed dryer has a regular pattern of gas diffuser nozzles 12 each fixed in apertures

2

14 by means of nuts 16 turned on the lower ends 18 of its tubular shank 20. Shank 20 contains a central passage 22 and has an upper shoulder 24 which rests on the top surface of partition plate 10. Shoulder 24 has two flats 25 formed thereon to accommodate a wrench when nozzle 10 is being installed or adjusted. The upper portion 26 of shank 20 above shoulder 24 has threads 28 formed thereon and an even number of castellations 30 cut therein, the castellations 30 having an even number of radial slots 32 and upstanding longitudinal projections 34.

Over the upper portion 26 there is screwed downward the cap 40 which has a pointed top 42 with a downward slope of its sides greater than 30 degrees. This prevents any powder or particle buildup on a top 42 in front of the escaping gas passing through nozzle 12. A buildup of powder or other particles to be dried in an upward flow of hot gas can result in the particles fusing together and aggregating to require the shutdown and cleaning of the nozzles.

20 The inside of cap 40 contains threads 44 which receive the threads 28 of castellations 30. The edge of top 42 projects well beyond a cylindrical skirt 46 except where two flats 56 are formed in it to enable a wrench to turn cap 40. Cylindrical skirt 46 contains an oppositely disposed pair of apertures 48 to receive a locking pin 50. Pin 50 has a head 52 and a shank 54. The projecting end of shank 54 may be bent over to hold pin 50 in place. Shank 54 passes through apertures 48 and a pair of slots 32 of castellations 30 to lock the cap 40 from rotation.

25 From the foregoing, it may be seen that the cap 40 may be screwed upward or downward to adjust the effective size of the slots 32 appearing below skirt 46 which serve as circumferentially located orifices for gas flow from each nozzle 12. The castellations 30 also serve as a locking means to receive the locking pin 50. Nozzle 12 and locking pin 50 are preferably fabricated from stainless steel to resist corrosion.

30 While this invention has been shown and described in the best form known, it will nevertheless be understood that this is purely exemplary and that modifications may be made without departing from the spirit and scope of the invention.

35 What is claimed is:

1. An adjustable nozzle to pass gas through a partition plate of a fluid bed dryer comprising, in combination,
  - (a) a tubular shank having a lower portion adapted to pass through and be fixed to a partition plate,
  - (b) an annular shoulder at the upper end of said shank to rest on said partition plate,
  - (c) a castellated upper end of said tubular shank projecting above said shoulder, said castellated upper end containing radial slots and having upstanding projections therebetween, said castellated upper end having external threads formed thereon,
  - (d) a pointed cap having sides sloping downward at an angle greater than 30 degrees, said cap having a cylindrical skirt extending downward below said cap, said cap and said skirt containing an internal threaded opening adapted to be screwed about said castellated upper end of said shank, said cylindrical skirt containing transverse oppositely disposed locking apertures, and
  - (e) a locking pin extending through said locking aper-

tures and through oppositely disposed radial slots in the castellated upper end of said shank, the screwing of said cap upward and downward on said castellated upper end of said shank enlarging and restricting the exposed length of said radial slots below said skirt of said cap, the exposed length of said radial slots serving as gas exit orifices.

2. The combination according to claim 1 wherein the lower portion of said shank is threaded.
3. The combination according to claim 2 wherein the 10 sides of said pointed cap and the sides of said annular shoulder have oppositely disposed flats formed therein.
